United States Patent Office

Des. 229,678

Patented Dec. 25, 1973

229,678

ARCHITECTURAL UNIT

Mark L. Hildebrand, Altadena, Calif.
(157 Bowers Hill Road, Oxford, Conn. 06483)

Filed Sept. 1, 1971, Ser. No. 177,196

Term of patent 14 years

Int. Cl. D25—01

U.S. Cl. D13—1 J

FIG. 10.

FIG. 1 is a top view of my architectural unit.
FIGS. 2 and 3 are perspective views of my architectural unit.

FIGS. 4 and 5 are, respectively, the side and back views of the architectural unit of FIG. 3.

FIG. 6 is a cross-sectional view through 6—6 of FIG. 3.

FIGS. 7, 8 and 9 are, respectively, cross-sectional views through 7—7, 8—8 and 9—9 of FIG. 6.

FIG. 10 is a perspective view of my architectural unit.
I claim:

The ornamental design for an architectural unit, substantially as shown.
